UNITED STATES PATENT OFFICE.

CLARENCE B. FROST, OF CAMBRIDGE, MASSACHUSETTS.

PACKAGE-SEALING APPARATUS.

No. 848,735.

Specification of Letters Patent.

Patented April 2, 1907.

Application filed January 28, 1907. Serial No. 354,449.

To all whom it may concern:

Be it known that I, CLARENCE B. FROST, of Cambridge, in the county of Middlesex and State of Massachusetts, have invented certain new and useful Improvements in Package-Sealing Apparatus, of which the following is a specification.

This invention relates to package-sealing apparatus.

15 The object of the invention is to provide improved means for directing a strip of binding-tape to a device for rendering the tape adhesive and thence to the package which is to be sealed, including improved means for retaining the tab end of the strip projecting in a position convenient for use, but out of contact with said device.

To this end the invention comprises two surfaces spring - pressed together between 20 which the tape passes, arranged at such an angle and position that the tape on issuing therefrom is projected over the device for rendering it adhesive. On the farther side of the device the tape passes under a guide- 25 pin and through a swinging carriage, which supports the tab end when necessary, allows a slight forward and backward movement thereof, and at the same time readily permits removal of the tape from the carriage 30 for renewing the adhesive qualities of the projecting portion.

In the accompanying drawings, Figure 1 represents a side elevation of the apparatus, partly in section. Fig. 2 represents a plan view of the same with the upper part removed. Fig. 3 is an enlargement of a detail seen in front elevation.

Referring to the drawings, 10 represents a frame, in which is supported a device for rendering tape adhesive. As here represented, this consists of a water-pan 11, into which a wheel 12 dips, the surface of the wheel being covered with an absorbent material, so that moisture rises either by rotation of the wheel 45 or by capillary attraction and maintains the top surface thereof moist. It is contemplated that with this device tape will be employed in which a coating of gum or mucilaginous material has been applied to one 50 surface of the tape and dried thereon, requiring only the addition of moisture to make it adhesive; but it is obvious that the pan might contain mucilage instead of water or that another form of device for rendering the tape adhesive might be substituted.

55 The tape is marked 15 and when being

drawn forth passes between directing-plates 17 18, over moistening-wheel 12, under guide- 60 pin 19, through carriage 20, and thence out from the apparatus. The supply of tape may be drawn from any convenient source. A convenient method of supporting the directing- 65 plates 17 18 is shown, in which the under plate has a side ear 24 projecting downward, in which is a slot 22, preferably set at an in- 70 clination to the plane of the plate 18, and this is held in place by a screw 21, which passes through the slot into a support rising from the edge of the water-pan. The upper plate 17 is made of flexible spring material, 75 is at its rear end fast to a transverse bar supported at the top of the under plate, and at its forward end lies in parallel contact with the under plate, pressing against the same by the force of its spring characteristic in such 80 manner as to exert pressure upon the strip of tape passing between it and the under plate. The parallel surfaces thus formed constitute guides for the tape, which direct the tape issuing from between them in the direction of their parallelism. It is contemplated that the tape employed will have some degree of elasticity. When directed forward, as shown in Fig. 1, the tape rises somewhat, as shown by the full line, until the weight of the projecting portion overcomes the stiffness and bends downward, normally passing thus over and beyond the moistening device. When the projecting extremity is pulled, the tape is drawn more taut and comes into contact 90 with the top of the moistening device, from which it rises, owing to its elasticity, when the forward pull is relaxed.

The guide-pin 19 is a device intended to insure contact of the tape with the moistening-wheel and for this purpose is set so that the straight line between its under surface and the directing-plates intersects the moistening wheel, and when the tape is made taut by drawing outward it touches the upper surface of the moistening-wheel, as indicated by the dotted position 15'. The projecting end, which might sink into contact with the outer part of the moistening device, is supported upon the carriage, (shown in the drawings,) 100 which constitutes another feature of the invention and is conveniently arranged as follows: In the under side of the guide-pin a groove is milled to receive two hanging wires 20, one designed to support each edge of the 105 tape, these being hung on cross-pins 25, set therein and being free to swing thereon and

also preferably having freedom for a little to-and-fro motion in the direction of travel of the tape. The lower end of each wire is bent upward to form a rest or support 27 for the tape, close to each edge thereof. When the tape is being drawn forth, it normally presses upward against the under side of guide-pin 19. When not in use, it may fall and be supported at 27. If it be desired to remoisten the projecting tab end, which has passed the place where the moistening operation is normally performed, this may be accomplished by pushing it downward with the finger, when the side supports 27 swing outward, allowing it to be pushed down and touched to the outer surface of the moistening-wheel, after which it may be affixed to the package and as much additional tape as desired drawn forth. Upon raising the tab end the tape slips easily between the side supports, which swing outward for that purpose, and when the tape is brought against the guide-pin 19, as it necessarily is on being raised for severing by the blade 31, these supports automatically swing back under the tape to hold it upon its release, being balanced by the projecting ends 28.

Tape is found in practice to have varying degrees of elasticity and varying degrees of stiffness, in which case the height of its trajectory over the moistening device needs to be varied. It is one feature of the invention to accomplish this by adjusting the position of the directing-plates angularly or otherwise with respect to the moistening device. This is accomplished by virtue of the slot 22 in ear 24 and the pivot 21, which enable the

directing-plates to be turned at any angle and also to be raised or lowered in conformity with the needs of the particular variety of tape or to the particular conditions of weather, which, it is found, sometimes affect the tape from day to day.

I claim—

1. A device for rendering tape adhesive, in combination with plates set approximately in parallelism, engaging the tape on opposite sides and directing it over and normally out of influence of said device.

2. A device for rendering tape adhesive, in combination with plates arranged to engage opposite sides of the tape and direct the tape, fixed pivotally near said device, whereby by adjustment of the plates about the pivot the tape may be directed at varying angles over said device.

3. A device for rendering tape adhesive, in combination with a stationary guide for tape arranged to direct tape over said device, and means to adjust the position of said guide angularly with respect thereto.

4. A device for rendering tape adhesive, in combination with a support for the tape issuing therefrom, comprising swinging rests therefor, one normally under each edge of the tape and swinging sidewise to permit passage of the tape to and from its normal position.

In testimony whereof I hereto affix my signature in presence of two witnesses.

CLARENCE B. FROST.
